REFRIGERATION

Ransom H. Beman, Detroit, Mich., assignor, by
mesne assignments, to Nash-Kelvinator Cor-
poration, Detroit, Mich., a corporation of
Maryland

Application August 11, 1931, Serial No. 556,420

6 Claims. (Cl. 62—126)

This invention relates to household and other refrigeration apparatus and particularly to the construction and arrangement of refrigerant evaporating units and metering devices employed in such apparatus.

An object of the invention is to provide a refrigerant evaporating unit which may be constructed of sheets of metal welded together and bent to form a compartment for the reception of ice trays and with which structure a refrigerator may be cooled by air circulating by natural draft or otherwise against the exterior surface thereof.

Another object of the invention is to provide a refrigerant evaporator embracing a header or disengaging space wherein evaporated refrigerant may collect in a region above the liquid refrigerant level and which header may be constructed in a complete and operative form before the sheets are bent to form an enclosure.

Another object of the invention is to provide a refrigerant evaporator which may be manufactured in the form of a relatively flat plate-like structure which thereafter may be bent into any desired form.

Another object of the invention is to provide a sheet metal evaporator structure having a plurality of parallel passages therein for the distribution of refrigerant liquid and to which structure liquid refrigerant is supplied in a relatively low region.

Another object of the invention is to provide a refrigerant evaporating unit which may be supplied with liquid by a high side float type of metering device located in the interior of a compartment to be refrigerated and supported directly by the evaporating unit.

Another object of the invention is to provide a brine receiving vessel for a sheet metal refrigerant evaporating unit which vessel when properly filled with liquid will tend to increase the period between cycles of operation of the refrigerating mechanism.

For a better understanding of the invention reference may now be had to the accompanying drawings forming a part of this specification, in which:

Figure 1 is a front elevational view of a refrigerator with a portion of the door and machine compartment thereof broken away so that the refrigerating mechanism thereof is visible;

Figure 2 is a cross sectional view of the refrigerant evaporating unit illustrated by Figure 1;

Figure 3 is a fragmentary longitudinal sectional view of the refrigerant evaporator illus-

trated by Figures 1 and 2 and taken substantially on line 3—3 of Figure 2;

Figure 4 illustrates another form of the invention in which a refrigerant evaporating unit is suspended directly from the refrigerator lining by flanges formed at the extremities of a metallic sheet from which the evaporating unit is constructed;

Figure 5 is a fragmentary cross sectional view of the evaporating unit structure illustrated by Figure 4 and taken substantially on line 5—5 thereof;

Figure 6 is a fragmentary cross sectional view of a refrigerator illustrating another form of evaporator embracing the invention disclosed herein;

Figure 7 is a fragmentary cross sectional view of the evaporator and refrigerator disclosed by Figure 6;

Figure 8 is a plan view of an evaporator at one stage in its construction;

Figure 9 is an end elevational view partly in cross section of the evaporator disclosed by Figure 8 and embracing a phantom figure showing how the evaporator is formed;

Figure 10 is a cross sectional view of the incomplete evaporator illustrated by Figure 8 and taken substantially on line 10—10 thereof;

Figure 11 illustrates a portion of the evaporator element shown by Figure 9 and taken substantially on line 11—11 thereof.

Referring more particularly to the drawings, Figure 1 illustrates an insulated cabinet 16 having an opening 17 for the reception of food products etc. to be refrigerated and which is normally closed by a door 18 suspended by hinges 19 and secured in position by a latch 21. An upper wall 22 of the refrigerator 16, which may or may not be removable, is adapted to support a refrigerant condensing unit 23, the principal elements of which are a motor 24, a compressor 26 and a condenser 27.

The motor 24 is provided with a grooved pulley, not shown, which drives the compressor 26 by means of a belt 28 operatively associated with a combined compressor driven pulley and fly wheel 29. The drive pulley of the motor 24 also has secured thereto a fan 21 adapted to discharge a blast of air against the condenser 27 for cooling the latter. The motor 24, compressor 26, and condenser 27 all are rigidly secured to a metallic base plate 31 which rests upon the upper refrigerator wall 22. Compressed refrigerant vapor delivered by the compressor 26 is discharged through a conduit 32 into an upper portion of the con-

denser 27 from whence it is in turn discharged through a conduit 33 into a high side float 34 located in the interior of the refrigerator 16.

The float casing 36 is provided with a threaded opening at its lower extremity engaging an annular coupling 37 which in turn engages a threaded opening in a refrigerant evaporator 38. Brackets 39 secured rigidly to the upper wall 22 of the refrigerator 16 in turn are secured to the evaporator 38 thus supporting the latter and the float mechanism 34. The refrigerant vapor evaporated in the evaporating unit 38 is exhausted therefrom through a conduit 41 to the suction side of the compressor 26.

15 The float valve mechanism 34 comprises essentially a casing 36, hereinbefore referred to, which is cylindrical in formation and threaded at its upper extremity to receive a cover 42 to which the conduit 33 is connected by a coupling 43. 20 The cover 42 has a centrally disposed opening 44 which provides a communicating passage between the interior of the conduit 33 and the casing 36 and through which refrigerant liquid condensed in the condenser 27 is discharged into the casing 36 of the float valve mechanism 34.

25 Disposed within the interior of the casing 36 and adapted to be buoyed up by the liquid refrigerant therein is a relatively light float 46 having an axially arranged passage 47 therein. An upper portion of the passage 47 is occupied by a needle valve 48 secured rigidly to the float by flanges 49. The lower portion of the passage 47 is adapted to receive slidably the upper extremity of a tubular member 49, the lower end of 30 which is permanently secured to the casing 37 by threads formed thereon which engage the threaded lower portion of the casing. The upper end of this member is provided with an annular seat 51 adapted to cooperate with the needle 48 to close the passage through the member 49 and consequently the communication between the interior of the casing 36 and the interior of the evaporator 38.

35 It is apparent that liquid refrigerant discharged from the conduit 33 into the casing 36 will gradually fill the latter to such an extent that the float 46 will be moved upwardly and the needle 48 moved away from its seat to permit any amount of refrigerant in excess of that 40 required to lift the float to flow downwardly through the passage in the tubular member 49 and into the evaporator 38.

45 The evaporator 38 is provided with a capillary expansion tube liquid feeding device 52 which is connected in parallel with the high side float 34, one of the ends of the tube communicating with the interior of the casing 36 on one side of the needle valve 48 while the opposite end thereof communicates with the evaporator as indicated at 54. It is apparent that the liquid 50 or gaseous refrigerant always will flow through the expansion tube 52 but inasmuch as the latter is of very small cross sectional area and of great length, the amount of refrigerant which 55 can travel therethrough will be considerably less than the amount of liquid normally supplied by the condensing unit. Under such circumstances liquid will gradually accumulate in the interior of the casing 36 until it elevates the float and the surplus thereof flows through the tubular member 49.

70 When the condensing unit is not in operation the expansion tube 52 will entirely drain the liquid from the casing 36 into the evaporator 38 and then will discharge gaseous refrigerant

until such time as the pressure is reduced to a considerable degree. In other words, the expansion tube 52 serves as an unloading device for the condensing unit 23 and hence it is possible to employ a motor having a relatively low starting torque.

75 The evaporating unit 38 consists essentially of interior and exterior metallic sheets 56 and 57 respectively which preferably are assembled to produce an evaporator according to the method 10 illustrated by Figures 8, 9, 10 and 11. The exterior sheet 57, for example, is provided throughout its length with a plurality of parallel depressions or corrugations 58 which terminate in a semi-cylindrical depression, header or manifold 59 extending across the sheet midway between the extremities thereof. In other words, the depression 59 intersects all of the depressions 58 midway between their opposite ends. The parallel depressions or passages 57 and the transversely disposed passage 59 all are formed, for example, by employing a die while the sheet is substantially planar. The sheet 56 is provided with relatively large semi-cylindrical depressions, 15 passages or headers 61 and 62 adjacent the opposite ends of the sheet and extending transversely thereof, relative to the parallel passages 58 in the sheet 57. The sheet 56 also is provided with a relatively small depression 63 on one of its edges and intermediate the ends of the transverse depression 59 in the sheet 57 to provide a relatively round opening for the reception of an internally threaded ring 64.

20 Thus preformed, the sheets 56 and 57 are disposed one upon the other and welded around their peripheries and along the contacting portions thereof between the depressions 58 in the sheet 57. The flat unit thus assembled is then bent in regions designated by the numerals 66 and 67 to provide a water freezing compartment 25 of the usual form.

25 Intermediate the opposite ends of the headers 61 and 62 are formed flanged openings 68 and 69 the extremities of which are welded together 30 after the evaporator is formed to provide a means of communication between the two headers. Brackets 71 may be welded on the inside shell 56 along the length of the evaporator in such manner as to provide supporting means for metallic plates or shelves 72 on which ice trays 73 35 are positioned. Ebullators 74 for initiating evaporation of refrigerant liquid are adapted to be positioned if desired in the depression or channel 59 with which the lower extremities of the parallel passages 58 communicate. In the operation of the evaporator relatively warm refrigerant liquid when discharged into the channel 59 immediately comes in contact with relatively cold refrigerant in the evaporator and with the ebullators 74 after which its temperature is rapidly reduced by evaporation. The refrigerant vapor bubbles so formed flow upwardly 40 through the passages 58, and violently agitate the liquid in the passages 58 thus preventing the superheating thereof.

45 Figures 4 and 5 illustrate another form of evaporator embracing the invention in which the outside sheet 57 projects a substantial distance beyond the ends of the inside sheet 56 as indicated 50 at 74, thus providing hangers for supporting the evaporating unit directly from the upper insulated wall 22. The hangers terminate in flanges 76 bent either outwardly or inwardly as desired 55 and which are secured to a sheet metal lining 77 60

of the cabinet by bolts 78. The flanges and the lining, however, are separated either at intervals or entirely throughout the length thereof by rubber or other insulating spacing material or strips 79. In this form of the invention the extremities of the evaporator are not bent inwardly as in the form previously described, but the headers 61 and 62 are connected together by a tube 81 inserted and welded in the flanges 68 and 69. The tube 81 in this instance communicates with the suction line 41 through which refrigerant vapor is exhausted from the evaporating unit to the condensing unit. A high side float 82 in this instance and principally for the purpose of illustration is located outside of the refrigerator lining and is connected to the flange 64 at the lower extremity of the evaporator by a liquid line 83. A shelf, not shown, for supporting an ice tray in this evaporator is adapted to rest upon a pair of projections 84 formed in the inner shell 56 longitudinally of the evaporator.

In the form of the invention illustrated by Figures 6 and 7 the inner shell 56 is constructed from a perfectly flat piece of sheet metal while the outer shell is constructed from a similar sheet in which a continuous depression or passage is formed. When these sheets are assembled, welded and bent into the proper shape another shell 86 having parallel passages or depressions 87 may be positioned about the structure and welded thereto at its periphery. The region between the shells 57 and 86 may be employed for the reception of a suitable holdover liquid such as brine, for example, which may be introduced therein through openings 87 normally closed by caps 88. This type of evaporator, which normally is employed in a dry refrigerating system, is provided with a coupling 89 at one end of the sinuous passage formed between the sheets 56 and 57 and to which the suction line 41 is attached. The opposite extremity of the sinuous passage is provided with a similar coupling 91 to which an automatic or a thermostatically controlled expansion valve 92 is secured. The expansion valve, like the float valves heretofore referred to, is supplied with liquid from the condensing unit through the liquid line 33. In this type of refrigerating system a cloud of refrigerant consisting of finely divided particles of liquid, is introduced by the expansion valve 91 into the sinuous passage formed between the sheets 56 and 57 and as it proceeds through the passage it absorbs heat and is changed into refrigerant vapor before reaching the end to which the suction line 41 is attached.

While in this specification a number of forms of evaporators and other elements of refrigerating systems have been disclosed and also a method or process of constructing evaporators, it is apparent that the invention may assume other forms or embodiments within the scope of the appended claims.

I claim:

1. Refrigerating apparatus comprising insulated walls forming a storage chamber to be cooled, evaporating means for cooling said chamber, said means comprising a pair of nested sheet metal casings, spaced apart but joined at their peripheries and at spaced intervals intermediate their peripheries to provide a relatively shallow refrigerant chamber, one of said casings extending beyond the confines of the other, and being secured to one of the insulating walls for supporting the evaporating means.

2. A sheet metal evaporator comprising an

outer one piece shell and an inner one piece shell bent to form the side and bottom walls of a sharp freezing chamber, arcuate depressions formed parallel to and spaced from the ends of one of said shells and also spaced from the front and back edges of said shell, said arcuate depressions cooperating with the other shell to form headers located at the ends of the shells but adjacent each other due to the bent form of the evaporator, embossed portions formed in one sheet and 10 extending around the side and bottom walls of the evaporator and connecting the two headers, and a connecting T forming a common refrigerant conduit between said two headers.

3. A sheet metal evaporator comprising an 15 outer one piece shell and an inner one piece shell bent to form the side and bottom walls of a sharp freezing chamber, arcuate depressions formed parallel to and spaced from the ends of one of said shells and also spaced from the front 20 and back edges of said shell, said arcuate depressions cooperating with the other shell to form headers located at the ends of the shells but adjacent each other due to the bent form of the evaporator, embossed portions formed in one 25 sheet and extending around the side and bottom walls of the evaporator and connecting the two headers, said shells being welded together around the front and back peripheries and across the end peripheries, and a connecting T forming a 30 common refrigerant conduit between said two headers.

4. A sheet metal evaporator comprising an outer one piece shell and an inner one piece shell bent to form the side and bottom walls of a sharp freezing chamber, arcuate depressions formed parallel to and spaced from the ends of one of said shells and also spaced from the front and back edges of said shell, said arcuate depressions cooperating with the other shell to form headers located at the ends of the shells but adjacent each other due to the bent form of the evaporator, embossed portions formed in one sheet and extending around the side and bottom walls of the evaporator and connecting the two headers, said shells being welded together around the front and back peripheries and across the end peripheries, a connecting T forming a common refrigerant outlet between said two headers and an inlet connection formed at the bottom of the evaporator and communicating with the embossed portions in the bottom wall of the evaporator.

5. A sheet metal evaporator comprising an outer shell and an inner shell each formed substantially in the flat and bent after welding to form a U-shaped sharp freezing chamber, an embossed portion in one shell consisting of an arcuate depression spaced from an edge of the shells and cooperating with the other shell to form a header, an embossed portion in one shell spaced from a different edge of said shells and consisting of an arcuate depression cooperating with the other shell to form another header, embossed portions in one shell and forming refrigerant passageways leading from each header and extending over the exposed surface of the shell forming the sharp freezing chamber, said headers being completely confined within the edges of said shells, a substantially continuous weld around the periphery of the shells to completely seal the evaporator with the exception of inlet and outlet connections, and connecting means for maintaining a common refrigerant level in both headers.

6. A sheet metal evaporator comprising an outer one piece shell and an inner one piece shell bent to form a sharp freezing chamber, an embossed portion in one shell consisting of an arcuate depression spaced from an edge of the shells and cooperating with the other shell to form a header, an embossed portion in one shell spaced from a different edge of said shells and consisting of an arcuate depression cooperating with the other shell to form another header, embossed portions in one shell and forming refrigerant

passageways leading from each header and extending over the exposed surface of the shell forming the sharp freezing chamber, said headers being completely confined within the edges of said shells, a substantially continuous weld 5 around the periphery of the shells to completely seal the evaporator with the exception of inlet and outlet connections, and connecting means for maintaining a common refrigerant level in both headers. 10

RANSOM H. BEMAN.
